UNITED STATES PATENT OFFICE.

JOHN HAYS, OF UNIONTOWN, PENNSYLVANIA.

UMBRELLA.

No. 869,082.

Specification of Letters Patent.

Patented Oct. 22, 1907.

Application filed April 26, 1907. Serial No. 370,383.

To all whom it may concern:

Be it known that I, JOHN HAYS, a citizen of the United States of America, residing at Uniontown, in the county of Fayette and State of Pennsylvania, have 5 invented certain new and useful Improvements in Umbrellas, of which the following is a specification, reference being had therein to the accompanying drawing.

This invention relates to improvements in umbrellas, and the invention has for its object to provide an umbrella that can be folded into a comparatively small parcel whereby it can be carried in a coat pocket, valise or trunk.

My improved umbrella is constructed whereby it 15 can be easily and quickly folded and maintained in a folded position until it is desired to use the same.

The umbrella is of a simple, strong and durable construction, and highly efficient for the purposes for which it is intended.

20 The detail construction entering into my improvement will be hereinafter more fully described and then specifically pointed out in the appended claims.

Referring to the drawing forming part of this specification, like numerals of reference designate corresponding parts throughout the several views, in which:

Figure 1 is an elevation of a portion of an umbrella constructed in accordance with my invention, the umbrella being partly broken away and partly shown in section, Fig. 2 is an elevation of a portion of the umbrella folded, one of the ribs thereof being shown in section, Fig. 3 is a detail sectional view illustrating the connection between the stretchers and the ribs.

30 My improved umbrella consists of a tip section 1, and a handle section 2, said sections being pivotally connected together by a link 3 arranged in the slotted confronting ends 4 of the sections 1 and 2.

The tip section 1, of the umbrella stick carries an outer notched band 5, to which are connected the cover supporting ribs of my umbrella. For clearness of 40 illustration, I have simply illustrated one of the ribs and one of the stretchers of the umbrella, it being understood that any desired number of ribs can be used. Each rib consists of a channel shaped telescopic section 6, and a rod section 7, the section 7 being provided 45 at its inner end with a band 8 having depending pierced lugs 9, which protrude through an open slit in a sleeve 11 the latter loosely mounted upon the telescopic section 6 and provided with spaced ears 10. The pierced lugs 9 of the band 8 and the spaced ears 10 of the sleeve 50 11 are pivotally connected to a stretcher 12, said stretcher being pivotally connected in turn as at 14, to

a runner 15 movably mounted upon the tip section 1 of the umbrella stick.

Fixed at one end to the section 1 of the umbrella stick by an auxiliary notched band 16 is an auxiliary 55 stretcher 17, and connecting at the other end with a band 18 fixed upon the stretcher 12. Interposed between the runner 15 and the auxiliary notched band 16 is a coiled spring 19, said spring surrounding the section 1 of the umbrella stick. The runner 15 is maintained in an elevated position by a conventional form of resilient holder 20, said holder receding into a groove 21 formed in the section 1 of the umbrella stick when it is desired to lower the runner. Immediately upon the holder 20 being pressed into the groove 21, the coiled 60 spring 19 surrounding the section 1 of the umbrella stick forces the runner 15 downwardly upon the stick 1, and as the auxiliary stretcher 17 has its upper end fixed to the auxiliary notched band 16, the lowering of the inner end of the stretcher 12 causes the outer end 70 of the same to travel inwardly and upwardly upon the channel-shaped telescopic sections 6 of the ribs.

It will be observed that the section 7 of the rib is moved upwardly within the telescopic section 6 and that the rib of the improved umbrella herein described 75 occupies approximately one-half the space, considering length, compared to the rib of ordinary umbrella. The handle section 2 of the umbrella stick can then be folded, whereby the umbrella will be approximately 80 one-half the length of an ordinary umbrella.

I do not care to confine myself to the manner in which the cover is secured upon the umbrella ribs, or to the material from which the umbrella is constructed.

What I claim and desire to secure by Letters Patent, 85 is:

1. A folding umbrella consisting of a stick, an outer notched band carried by said stick; an auxiliary notched band carried by said stick and spaced from said outer notched band, a runner slidable upon said stick, a spring operating between said runner and said auxiliary notched 90 band, a spring actuated holder operating to maintain said runner in elevated position, telescopic rib sections swinging at one end from said outer notched band, rib sections slidable in said telescopic rib sections, main stretchers pivotally united at their ends respectively to said runner 95 and to said sliding rib sections, and auxiliary stretchers swinging at their ends respectively from said auxiliary notched band and said main stretchers.

2. A folding umbrella consisting of a stick, an outer notched band carried by said stick, an auxiliary notched 100 band carried by said stick and spaced from said outer notched band, a runner slidable upon said stick, a spring operating between said runner and said auxiliary notched band, a spring actuated holder operating to maintain said runner in elevated position, telescopic rib sections swing- 105

ing at one end from said outer notched band, rib sections
slidable in said telescopic rib sections, sleeves slidable
upon said telescopic rib sections and provided with de-
pending ears, bands connected to said sliding rib sections
5 and each provided with an ear extending between the ears
of said sleeves, main stretchers pivotally united at one
end to said sleeves and sliding rib sections by pivots ex-
tending through the depending ears thereof and pivotally
united at their other ends to said runner, and auxiliary

stretchers swinging at their ends respectively from said 10
auxiliary notched band and said main stretchers.

In testimony whereof I affix my signature in the presence
of two witnesses.

JOHN HAYS.
